THOMAS WHITEHEAD HAWKINS, OF RUABON, WALES

MACHINE FOR WASHING WOOL AND OTHER FIBROUS MATERIALS

Application filed April 16, 1928, Serial No. 270,492, and in Great Britain April 20, 1927.

This invention relates to machines for washing wool and other fibrous materials, of the kind in which the material under treatment is propelled through a bath of cleansing liquor by means of prongs carried by one or more frames adapted to be oscillated vertically and horizontally by primary driving mechanism.

This oscillation of the prong frame or frames has hitherto been effected in some machines by two separate mechanical motions, that is to say, vertical movement has been imparted by revolving cam mechanism and horizontal movement by cranks or eccentrics and connecting rods; arrangements being made, when a main frame and also an auxiliary or delivery frame are employed, to operate said frames alternately.

In other machines oscillation of the prong frame has been produced by a single motion embodying a pair of rotary discs having wrist-pins to which the prong frame is connected.

This invention has for its objects to simplify and reduce the number of parts of the mechanism for actuating the prong frame or frames, to improve the mechanism and to increase the efficiency and output of the machine.

In the revolving cam mechanism previously employed there is not infrequently, at a certain point, lost motion due to the parts being temporarily unsupported by the revolving cam or cams and there is a consequential tendency for the bowl in contact with each revolving cam to drop a short distance whereby the mechanism sustains a shock that in time results in damage to the parts. Again, the revolving actuating mechanism hitherto employed has not resulted in the imparting of the maximum effective stroke to the points of the prongs.

These disadvantages, among others, are overcome by the present invention.

Accordingly, the rotary movement of the primary driving mechanism of a machine of the type specified for washing wool or other fibrous materials, is converted into a succession of rectilinear displacements, of the supports of the prong frame or frames, corre-

sponding to a simulacrum of the oscillatory path to be described by the points of the prongs which propel the material through the cleansing liquor, in such manner that the maximum attainable effective stroke is imparted to the frame or frames when passing forwardly through the bath.

To this end the supports of the prong frame or frames is or are travelled around one or more endless tracks whereof the configuration of each is a simulacrum of the path to be described by the points of said prongs in such a manner that said frame or frames is or are caused to oscillate uniformly and without lost motion.

One constructional embodiment of the invention is illustrated by way of example in the accompanying drawings which show a machine whereof the main structural features are more or less conventional, and wherein Figure 1 is a side view, Figure 2 is a plan view, and Figure 3 is an end view partly in section. Figure 4 is a perspective view of a portion of that form of the invention which is appropriate to an auxiliary frame moving over an inclined bottom.

Figure 5 is a detailed side elevation of one of the cam tracks for the auxiliary prong frame,

Figure 6 is a detailed side elevation of one of the cam tracks for the main prong frame, and

Figure 7 is a vertical transverse section taken on the line 7—7 of Figure 6 in the direction of the arrow points.

The machine comprises a rectangular bath or bowl 1 containing the washing liquor and having the usual false bottom 2 which is inclined upwardly at 3 towards the squeezing rolls 4, 4.

In the construction illustrated, the fibres to be washed are propelled through the bath or bowl 1 by means of a main oscillating prong frame 5 operating over the horizontal false bottom 2 and an auxiliary oscillating prong frame 6 operating over the inclined false bottom 3, the frame 5 having the ordinary series of downwardly depending prongs 7 and the frame 6 having similar prongs 8; the two frames being formed with relatively

spaced parallel bars arranged as shown in Figure 2 of the drawings in interpositioned relationship and also so as to operate alternately.

5 9 and 10 are respectively a loose and a fast belt pulley adapted to receive a driving belt (not shown) whereby power is transmitted to the machine from an electric motor or other convenient source, said pulleys being mounted on a shaft 11 supported in appropriate bearings transversely above the bath 1 and having keyed thereon pinions 12, 12, which mesh with spur wheels 13, 13, keyed upon stub axles 14; said mechanism constituting the primary driving mechanism of the machine.

20 Said stub axles 14, 14, are accommodated respectively in bearing bosses 15, 15, formed in a pair of castings 16, 16, adapted to be bolted to or otherwise suitably secured opposite to one another upon the flanged upper edges of the side walls of bath 1; each casting 16 being formed integrally with an up-standing pedestal or bracket member 17. 25 Upon a machined seating on the inner face of each casting 16 there is bolted at 18 concentrically with each stub axle 14, a quadrilateral cam groove or track 19 of substantially rectangular contour but radiused at its 30 corners (see Figures 6 and 7).

35 Secured upon the inner end of each stub axle 14 so as to be rotatable therewith, there is a slotted link or lever 20 in which operates a slide-block or cross-head 21 through which passes a rod 22 extending transversely across the bath and connecting the mutually opposite cross-heads 21, and said rod 22 terminates in, or has mounted on its two ends, rollers 23, 23, each of which is accommodated in one 40 of the aforesaid quadrilateral cam grooves or tracks 19.

45 At or near its rear extremity the main prong frame 5 is attached by means of clamping members 24, 24, as more clearly shown in Figures 2 and 3 to the aforesaid transverse rod 22, while its forward extremity is suspended by rods 25, 25, from pivotally mounted bell-crank levers 26, controlled by balance weights 27, which levers 26 are articulated to 50 similar pivotally mounted bell-crank levers 28 connected by rods 29 to the transverse rod 22 and controlled by balance weights 30, (see Figures 1, 2 and 3).

55 For the support and operation of the forward or auxiliary prong frame 6 a similar arrangement of parts is provided, that is to say, a transverse shaft 11a carries pinions 12a, 12a, which mesh with spur wheels 13a, 13a, borne by stub-axles 14a, 14a, carried by 60 oppositely disposed castings 16a each having an upwardly projecting stem or pedestal member 17a which combine with members 17, 17, to support two longitudinal beams 31, 31, (see Figures 1 and 2).

65 The aforesaid shaft 11 has keyed upon it

a sprocket wheel 32 and a similar sprocket wheel 32a is keyed upon shaft 11a which receives rotary motion by means of an endless chain 33 connecting said two sprockets.

Bolted at 18a to the faced inner surface of each casting 16a is a quadrilateral cam groove or track 19a radiused at its corners and differing in contour from the former cam grooves 19 in that its lower run is inclined correspondingly with the inclination of the 75 false bottom 3 of bath 1 (see Figures 4 and 5).

To the inner ends of stub axles 14a are secured slotted links or levers 20a in which operate slide-blocks or cross-heads 21a connected by a transverse rod 22a carrying at its 80 extremities rollers 23a adapted to run in the cam grooves 19a.

The rear extremity of each side member of the auxiliary prong frame 6 is secured at 24a to the transverse rod 22a and the frame is 85 supported forwardly by the rod 25a connected to pivotally mounted bell-crank levers 26a controlled by counter or balance weights 27a and articulated to bell-crank levers 28a which are connected by a rod 29a to the transverse 90 rod 22a and are also controlled by counter or balance weights 30a.

All the aforesaid bell-crank levers and balance weights are mounted on spindles journaled in suitable bearings bolted to the 95 longitudinal beams 31, 31, which constitute an overhead framing.

100 It will be seen that the rotary movement of the primary driving mechanism 11, 12, 13, 14, imparts angular movement to each pair of slotted links or levers 20, and 20a, whereby the rollers 23 and 23a are constrained to move around their respective cam grooves or tracks 19 and 19a and the slide-blocks or cross-heads 21, 21a are caused to slide in the 105 levers 20 and 20a, thus imparting to the prong frames 5 and 6 a sequence of horizontal and vertical displacements which constitute the oscillatory path through which each frame passes in order to fulfill its function. 110

115 In the case of the main prong frame 5, these displacements are made up of a downward vertical movement followed immediately by a forward horizontal movement parallel with the false bottom 2, followed by an upward vertical movement withdrawing the prongs 7 from the material in the bath, and finally a backward horizontal movement, throughout the whole of which movements the frame 5 is supported positively and is 120 so balanced that its passage is continuously smooth and uniform.

125 The displacements imparted to the auxiliary prong frame 6 (which is of course timed to function alternately with the effective stroke of the main prong frame 5) are analogous to those already described with reference to the main prong frame, except that the direction of the forward stroke of the auxiliary frame is upwardly inclined, and 130

the auxiliary prong frame being also supported positively and balanced throughout the whole of its travel, its movements are continuously smooth and uniform.

- 5 It will be seen that by reason of the even movement imparted to the two prong frames the machine is not subjected to any shocks during operation (such as are inseparable from constructions embodying independent 10 cam and crank motions), which is a considerable advantage in large and heavy machines, and, furthermore, owing to the lighter and more regular running of the frame a considerable reduction is effected in the 15 power necessary to drive the machine, from which it follows that the cost of running and renewing or repairing is materially diminished.

It will be manifest that the specific details 20 of construction are susceptible of modification or variation according to different practical requirements, and that, for example, two or more machines may be driven in tandem from a single primary driving mechanism.

What I claim is:—

1. A machine for washing wool and other fibrous materials comprising, a bath for containing cleansing liquor and fibrous material, an oscillatory frame having prongs projecting into the liquor to advance the fibrous material therein, frame supporting means, angularly movable guiding members slidably carrying said frame supporting means, rotatable members on said frame supporting means, a cam track fixed in relation to the frame and engaged with said rotatable members, and rotary driving mechanism connected to said angularly movable members and acting thereon to shift said rotatable members and frame supporting means around the cam track to move the frame and its prongs in a succession of rectilinear paths at least one of which is parallel with the bottom of the bath.

2. A machine for washing wool and other fibrous materials comprising, a bath for containing cleansing liquor and fibrous material, an oscillatory horizontal frame having depending prongs projecting into the liquor to advance the fibrous material therein, frame supporting means extending crosswise above the bath, slotted angularly movable guide members, blocks near the opposite ends of said frame supporting means and slidably mounted in said slotted angularly movable members, rotatable guide members on the ends of said frame supporting means, quadrilateral cam tracks fixed on the sides of said bath and engaging said rotatable members, and rotary driving mechanism connected to said slotted angularly movable guide members and acting thereon to shift said rotatable guide members and frame supporting means around said quadrilateral

cam track to move the frame and its prongs in a succession of rectilinear paths.

3. In a machine for washing wool and other fibrous materials, a bath for containing cleansing liquor and fibrous material and having an upwardly inclined end, a main oscillatory frame having prongs depending therefrom, an auxiliary oscillatory frame having prongs depending therefrom, said auxiliary oscillatory frame being located above said upwardly inclined end of said bath and moving alternately with respect to said main oscillatory frame, a pair of continuous quadrilateral rectilinear tracks fixed in relation to said frames and having their lower side parallel with the bottom of the bath, and a second pair of continuous quadrilateral rectilinear tracks fixed in relation to the frame and having their lower side parallel with said upwardly inclined end of the bath, slotted guide members rotatably mounted upon the bath and slidably supporting said frames, rollers engaging said frames respectively with said pairs of fixed quadrilateral tracks, and rotary driving mechanism actuating said slotted supporting members to drive said engaging rollers around said tracks to move the frames and their prongs in a succession of rectilinear paths.

4. A machine for washing wool and other fibrous materials comprising a bath to contain liquor and fibrous material, an oscillatory frame having prongs projecting into the liquor to advance the fibrous material therein, frame supporting means, angularly movable guiding members slidably carrying said frame supporting means, a quadrilateral cam track fixed in relation to the frame and engaging the frame supporting means to guide it in a succession of rectilinear paths, the configuration and position of said cam track being such that two of said rectilinear paths are normal to, and a third is parallel with the bottom of said bath, and rotary driving mechanism connected to said guiding members to shift said frame supporting means around the cam track to move the frame and its prongs in said paths.

5. In a machine for washing wool and other fibrous materials, having a bath to contain cleansing liquor and fibrous material, and an oscillatory frame provided with prongs projecting into the liquor to advance the fibrous material therein, a quadrilateral cam track fixed in relation to the frame and engageable with the same to guide it in a succession of rectilinear paths, the configuration and position of said cam track being such that two of said rectilinear paths are normal to, and a third is parallel with the bottom of said bath, and means for moving said frame in said paths.

In testimony whereof he affixes his signature.

THOMAS WHITEHEAD HAWKINS. 130
